(57) CLAIM

The ornamental design for a travel wrap, as shown and described.

DESCRIPTION

FIG. 1 is a top-down, front perspective view of a travel wrap;

FIG. 2 is a left side view of the travel wrap;

FIG. 3 is a right side view of the travel wrap;

FIG. 4 is a front view of the travel wrap;

FIG. 5 is a rear view of the travel wrap;

FIG. 6 is a top plan view of the travel wrap; and,

FIG. 7 is a bottom view of the travel wrap.

The evenly dashed broken lines depicting fringe extending from a bottom edge of the travel wrap show portions of the travel wrap that form no part of the claimed design.

The evenly dashed broken lines crossing surfaces (resembling a hem/stitching) of the travel wrap show portions of the travel wrap that form no part of the claimed design.

The dashed broken lines shaped in an "X" crossing surfaces (resembling a seam/stitching) of the travel wrap show portions of the travel wrap that form no part of the claimed design.

1 Claim, 5 Drawing Sheets
